UNITED STATES PATENT OFFICE.

WENZ TURKA, OF CRACOW, AUSTRIA-HUNGARY.

SAFETY-RAZOR.

1,147,054.

Specification of Letters Patent. Patented July 20, 1915.

Application filed July 8, 1913. Serial No. 777,956.

To all whom it may concern:

Be it known that I, WENZ TURKA, a citizen of the Austro-Hungarian Empire, residing at army backing establishment, Cracow, in the Kingdom of Galicia and Empire of Austria-Hungary, have invented new and useful Improvements in Safety-Razors, of which the following is a specification.

My invention relates to safety razors, in which the blade consisting of thin, flexible steel, and of flat shape, is gripped between two surfaces of a clamping and a guard member.

I am aware, that in the type of safety razors of such kind the guard and clamping members, which are in some cases flat, in others curved, are not always parallel with each other. But with these razors, having such non parallel surfaces, the width of blade exposed, and the angle at which the blade projects can either not be adjusted at all, or must both be adjusted together.

The object of the present invention is to provide a razor wherein the blade is gripped, as described, between a clamping and a guard member, but wherein the width of blade exposed and its angle can be adjusted independently of each other, as in some razors of other types. To this end I construct a clamping and a guard member so that they converge at their edges, to grip the blade, but have between them, along their central parts a cavity, within which the blade can be bent for the purpose of regulating the width of the part exposed without altering the angle of that part.

The invention is illustrated in the annexed drawings, which show one form of construction and in which—

Figure 1 is a perspective view of the razor, Fig. 2 a vertical section showing the parts assembled but not screwed up for use, Fig. 3 a vertical section of the upper part of the razor with the blade arranged over the adjusting bar, Fig. 4 a front view of the clamping member, Fig. 5 a similar view of the guard member, Fig. 6 a similar view of the adjusting bar, Fig. 7 a similar view of the blade, Fig. 8 a similar view of the outer handle member and Fig. 9 a similar view of the inner handle member.

In the drawing, *a* designates what may be called the clamping member, which is concave on one side, which I call the inside surface. From this inside surface project two bosses *b* and a screw-threaded shank *c*. The

flexible blade *d* has holes for these bosses and for the shank. The outer surface of the member *a* has a groove *e*.

The guard member, designated *f*, is of an undulating shape, and has teeth *g* along its edges. When the clamping and the guard member are placed together, as shown in Fig. 1, there is a channel or cavity between them, along the center, by virtue of the concavity of the one and the undulation of the other, but near their edges the parts converge to grip the blade *d*. The guard *f* has holes for the bosses *b*, and also a central hole for a screw-threaded, tubular shank *h* fixed to a bar *i*, which lies within the cavity referred to. The surfaces of this bar are shaped to fit alternatively against the inside surface of the clamp *a*, and against the guard *f*, and the bar *i* can be moved up and down a few millimeters between the two members. The bar has holes for the bosses *b*, and the shank *c* passes through the shank *h*. The blade may lie either under the bar *i*, as shown in Fig. 2, or over it, as shown in Fig. 3.

The parts are held together by two tubular handle members *l* and *p*, the member *p* lying partly within the cavity *m* of the member *l*. The member *l* is internally screw-threaded at *n* to engage with the shank *h*. Its front edge is marked with divisions forming a scale *o*, which can be made to register with a mark on the guard *f*. The member *p* is internally screw-threaded at *q* to engage with the shank *c*, and has a scale *r* marked on an enlarged part at its rear end, to register with a mark on the member *l*.

It will be seen that by turning the member *l*, the bar *i* can be moved up and down in the cavity between the clamping and the guard member. By this means the blade can be bent between the clamping and the guard member, so as to alter its effective width and the extent to which it projects from the edges of the members, the bar *i* being moved up or down, according to whether the blade lies over or under it. By turning the member *p* the clamp *a* can be moved up or down, and this regulates the angle at which the blade projects, at its edges. The two adjustments are quite independent, so that one can be made without affecting the other. The adjustments can be noted by means of the scales *o* and *r*, so that they can be easily reobtained after dis-

connecting the parts for cleaning. The groove *e* enables the razor to move more easily over the face of the user.

Having now particularly described and ascertained the nature of my invention and in what manner the same is to be performed I declare that what I claim as new and desire to be secured by Letters Patent is:—

1. In a safety razor the combination of a flexible blade, a clamping and a guard member, the guard member being of undulating shape, with a depression forming one wall of a cavity between the two said members, along the center of the same, and the interior surface of the clamping member having a concave shape on the inside surface forming the other wall of the said cavity and an adjustable bar in the cavity, arranged to bear on the blade and bend the same, the bar having outer surfaces corresponding to the walls of the said cavity.

2. In a safety razor the combination of a flexible blade, a clamping and a guard member, the guard member being of undulating shape, with a depression forming one wall of a cavity between the two said members, along the center of the same and the interior surface of the clamping member having a concave shape on the inside surface forming the other wall of the said cavity, an adjustable bar in the cavity, arranged to bear on the blade and bend the same, the bar having outer surfaces corresponding to the walls of the said cavity, a threaded shank on said clamping member, a threaded shank fixed to the said adjustable bar and two tubular, separately rotatable

screwed members, one within the other, one engaged with the said threaded shank of the clamping member and the other with the said threaded shank of the bar, whereby said clamping member and bar can be separately adjusted.

3. In a safety razor the combination of a flexible blade, a clamping and a guard member, the guard member being of undulating shape, with a depression forming one wall of a cavity between the two said members, along the center of the same and the interior surface of the clamping member having a concave shape on the inside surface forming the other wall of the said cavity, an adjustable bar in the cavity, arranged to bear on the blade and bend the same, the bar having outer surfaces corresponding to the walls of the said cavity, a threaded shank on said clamping member, a threaded shank fixed to the said adjustable bar and two tubular, separately rotatable screwed members one within the other, one engaged with the said threaded shank of the said clamping member and the other with the said threaded shank of the bar, whereby said clamping member and bar can be separately adjusted, said tubular members having scales marked thereon to indicate the adjustments.

In testimony whereof I affix my signature in presence of two witnesses.

WENZ TURKA.
